CLAIM

We claim the ornamental design for a pendant adapter, as shown and described.

DESCRIPTION

FIG. 1 is a perspective view of the design taken from above and showing the left side thereof;

FIG. 2 is a front view of the design;

FIG. 3 is a back view of the design;

FIG. 4 is a left side view of the design;

FIG. 5 is a right side view of the design;

FIG. 6 is a top view of the design; and,

FIG. 7 is a bottom view of the design.

The broken lines in the drawings illustrate portions of the pendant adapter in which the design is embodied, which form no part of the claimed design.
